Patented Jan. 14, 1975

234,079

TANDEM WING AIRPLANE

Philip C. Whitener, Seattle, Wash., assignor to
The Boeing Company, Seattle, Wash.

Filed Aug. 9, 1973, Ser. No. 387,216

Term of patent 14 years

Int. Cl. D12—07

U.S. Cl. D12—77

Fig. 2

Fig. 3

FIG. 1, is an upper forward perspective view of a tandem wing airplane depicting my new design;

FIG. 2, is a forward side perspective view;

FIG. 3, is a side perspective view; and

FIG. 4, is an upper aft perspective view thereof.

I claim:

The ornamental design for a tandem wing airplane, as shown and described.
